(57) **CLAIM**

The ornamental design for a ponytail volumizer, as shown and described.

DESCRIPTION

FIG. 1 is a front perspective view of a ponytail volumizer according to an embodiment;

FIG. 2 is a top elevational view of the ponytail volumizer of FIG. 1;

FIG. 3 is a bottom elevational view of the ponytail volumizer of FIG. 1;

FIG. 4 is a front elevational view of the ponytail volumizer of FIG. 1;

FIG. 5 is a back elevational view of the ponytail volumizer of FIG. 1;

FIG. 6 is a right side view of the ponytail volumizer of FIG. 1; and,

FIG. 7 is a left side view of the ponytail volumizer of FIG. 1.

The broken lines are for illustrative purposes only and form no part of the claimed design.

1 Claim, 4 Drawing Sheets(56)
